COMBINED NIPPLE AND NURSING BOTTLE FOR A BABY

Sten S. Swanson, 1741 Walnut Circle, Northbrook, Ill.

Filed July 14, 1960, Ser. No. 61,356

Term of patent 14 years

(Cl. D83—8)

FIG. 1.

FIG. 2.

FIG. 3.

FIG. 4.

FIGURE 1 is a front elevational view of a combined nipple and nursing bottle for a baby embodying my new design, the vertical line shading on the bottom of the carot representing contrasting color;

FIGURE 2 is a right side elevational view thereof, the left side being substantially the same;

FIGURE 3 is a rear elevational view thereof; and

FIGURE 4 is a top plan view thereof, the bottom not shown being substantially plain.

The dominant features of my design reside in the full-line portions of the drawing.

I claim:

The ornamental design for a combined nipple and nursing bottle for a baby, as shown and described.
